WOVEN WIRE BELT FOR PAPER MAKING MACHINES

Filed Dec. 12, 1929

INVENTOR.
NELSON W. WEBB.
BY
Henry Wattern.
ATTORNEY.

UNITED STATES PATENT OFFICE

NELSON W. WEBB, OF BELLEVILLE, NEW JERSEY, ASSIGNOR TO EASTWOOD WIRE CORPORATION, OF BELLEVILLE, NEW JERSEY, A CORPORATION OF NEW JERSEY

WOVEN-WIRE BELT FOR PAPER-MAKING MACHINES

Application filed December 12, 1929. Serial No. 413,575.

The present invention relates to woven wire belts, particularly for paper-making machines of the Fourdrinier type, and has for an object to provide an improved seam or jointure between the ends of the length of wire mesh, and whereby a substantially endless belt is produced. It is particularly proposed to secure the ends by welding, brazing or soldering in such manner that the joint will have substantially the same characteristics of porosity, flexibility and strength as the body of the wire mesh. 5

A further object is to provide a novel end structure for the wire mesh, whereby the joining of the ends may be carried out in a convenient, uniform and economical manner. 10

Another object is to provide a seam structure which will present an increased wear-resisting surface to the suction boxes over 15 which the belt passes.

With the above and other objects in view, embodiments of the invention are shown in the accompanying drawings, and these embodiments will be hereinafter more fully described with reference thereto and the invention will be finally pointed out in the claims. 20

In the drawings:

Fig. 1 is a plan view of a portion of a woven wire belt at the seam; 25

Fig. 2 is a longitudinal sectional view, taken along the line 2—2 of Fig. 1;

Fig. 3 is a bottom plan view;

Fig. 4 is a top plan view of a modified form of the invention; and 30

Fig. 5 is a sectional view, taken along the line 5—5 of Fig. 4.

Similar reference characters indicate corresponding parts throughout the several figures of the drawings. 35

Referring particularly to Figs. 1 to 3 of the drawings there is shown, greatly enlarged, a portion of the two ends of the wire cloth which are seamed together to form a belt, the portion, as shown, representing a piece of the belt which in its actual size is about $\frac{1}{6}$ of an inch in width. The wire cloth consists of warp wires 10 and weft wires 11 of brass, bronze, or other suitable material for the purpose. The end weft wire at one end of the cloth is removed and the warp wire ends which would normally be above the weft wire are bent downwardly as at 12, so that they are in line with the other warp wire ends, and are preferably curved, as shown, thus presenting a continuous upwardly disposed bearing forming a recess or groove along the edge of the belt. The end weft wire 13 at the other end of the belt is thereupon engaged in the bearing groove formed by the warp ends at the opposed end, the warp ends of one end being disposed between the warp ends of the other, and in this relation the ends of the belt are brazed, welded or soldered together. 40

While the brazing, welding or soldering may be done in any suitable manner, I preferably provide a solder coated end wire 13 inserted in the end of the cloth in substitution of a removed end weft wire, and which upon the application of heat will produce solder joints at the points of intersection with the warp wire ends, this method resulting in a strong, uniform union along the entire width of the belt, the interstices between the wires being at the same time maintained free of lumpy spots. 45

The seam or jointure according to my invention may be produced with facility, speed, and economy, and will have substantially the same strength, flexibility and porosity as the body of the wire mesh. The warp wire ends underlying the end weft wire provide an increased wear resisting surface so that the seam will not be subject to excessive wear and breakage through engagement with the suction boxes. 50

In Figs. 4 and 5 I have illustrated a modified form of the invention, in which the end weft wires are removed at both ends of the belt, the warp ends at one end which would normally be beneath the weft wire being bent, as at 14, so that they are in line with the other warp ends, while the warp ends at the other end which would normally be above the weft wire are bent, as at 15, so that they are in line with the other warp ends. One end of the belt is thus provided with an upwardly offset bearing at the under side, while the other end is provided 55

with a downwardly offset bearing at the upper side. These ends are overlapped with the warp wire ends staggered and with a weft wire 16 engaged with the opposed bearings, and are joined by brazing, soldering or welding. The weft wire 16 is preferably solder coated, so that upon the application of heat solder joints will be produced at the points of intersection with the warp wire ends.

10 I have illustrated and described preferred and satisfactory embodiments of the invention, but it will be obvious that changes may be made therein within the spirit and scope thereof, as defined in the appended claims.

15 Having thus described my invention what I claim and desire to secure by Letters Patent is:—

1. In a wire cloth belt, a length of woven wire cloth comprising warp and weft wires and having its ends adjacent, all of the warp wire ends at one end of said length of cloth being disposed in line with each other and engaged at one side of a weft wire 20 at the other end of the cloth, and means connecting said warp wire ends to said weft wire.

2. In a wire cloth belt, a length of woven wire cloth comprising warp and weft wires and having its ends adjacent, the warp wire ends at one end of said length of cloth being disposed in line with each other and having a bearing surface disposed upwardly and extending across the width of the 25 belt, said bearing surface being engaged by a weft wire at the other end of the cloth, said warp wire ends being connected to said weft wire by a heat-produced metallic union.

3. In a wire cloth belt, a length of woven wire cloth comprising warp and weft wires and having its ends adjacent, the warp wire ends at one end of said length of cloth being disposed in line with each other and having a bearing surface disposed upwardly, the warp wire ends at the other end being disposed in line with each other and having a bearing surface disposed downwardly, and a weft wire engaged with said bearing surfaces between said warp wire ends and connected thereto by a heat-produced metallic union.

4. In a wire cloth belt, a length of woven wire cloth comprising warp and weft wires and having its ends adjacent, the warp wire ends at one end of said length of cloth being disposed in line with each other and having a grooved bearing surface disposed upwardly and extending across the width of the belt, 40 said bearing surface being engaged by a weft wire at the other end of the cloth, said warp wire ends being connected to said weft wire by a heat-produced metallic union.

5. In a wire cloth belt, a length of woven wire cloth comprising warp and weft wires

and having its ends adjacent, the warp wire ends at one end of said length of cloth being disposed in line with each other and having a grooved bearing surface disposed upwardly, the warp wire ends at the other end being disposed in line with each other and having a grooved bearing surface disposed downwardly, and a weft wire engaged with said bearing surfaces between said warp wire ends and connected thereto by a heat-produced metallic union.

Signed at Belleville, county of Essex, and State of New Jersey, this 14th day of November, 1929.

NELSON W. WEBB. 8
